UNITED STATES PATENT OFFICE

161,418

MOLDING

Ben Bunin, River Edge, N. J., assignor to Product Design & Mfg. Corp., North Hackensack, N. J.

Application November 10, 1948, Serial No. 149,559

Term of patent 7 years

(Cl. D54—2)

To all whom it may concern:

Be it known that I, Ben Bunin, a citizen of the United States, residing at River Edge, in the county of Bergen and State of New Jersey, have invented a new, original, and ornamental Design for a Molding, of which the following is a specification, reference being had to the accompanying drawing, forming a part thereof.

Fig. 1 is a front perspective view of a molding, showing my new design.

Fig. 2 is a rear perspective view thereof.

In both views, a portion of the molding is broken away to indicate indefinite length.

I claim:

The ornamental design for a molding, substantially as shown and described.

BEN BUNIN.
